UNITED STATES PATENT OFFICE.

CHARLES L. SHINE, OF PROVIDENCE, RHODE ISLAND.

CURTAIN-SUPPORT.

1,118,157.

Specification of Letters Patent. Patented Nov. 24, 1914.

Application filed February 13, 1914. Serial No. 818,590.

To all whom it may concern:

Be it known that I, CHARLES L. SHINE, a citizen of the United States, residing at Providence, in the county of Providence and 5 State of Rhode Island, have invented a new and useful Improvement in Curtain-Supports, of which the following is a specification.

This invention relates to certain new and 10 useful improvements in curtain supports, and the primary object thereof is to provide an expandable and contractible spring mounting for the curtain, which spring mounting due to its expandable and contractible properties may be easily and 15 quickly accommodated to windows possessed of varying widths.

Further, the invention aims to provide a support which resiliently holds the curtain, 20 whereby if same is pulled by children or others, the curtain will be permitted to give so as to thereby not injure same.

In the drawings—Figure 1 is a front elevation of a window frame showing the present invention in position thereon, the rod which supports the curtain being shown in 25 longitudinal section. Fig. 2 is a section taken on the line 2—2 of Fig. 1, and Fig. 3 is a perspective view of one of the clips or 30 brackets.

There are two clips or brackets employed in carrying the invention into practice, each of which consists of a sheet metal plate formed to have a body portion 1, and opposite 35 side wings 2, the parts just mentioned seating flat against the front faces of the window frame. The side wings act to strengthen the structure and prevent twisting of the sheet metal. The front or outer exposed faces of the body and side wings are 40 further strengthened by a pressed out rib 3 which latter is preferably given a conformation that enhances the ornamental value and effect of the clips or brackets. The outer 45 ends of the bodies are extended at right angles at 4 to abut the side faces of the window frame and are provided at their free extremities with prongs 5 which extend parallel to the bodies and are forced into 50 the wood material of which the window

frame is constructed, so as to effectively sustain the clips or brackets in position. Small nails or pins 6 may be driven through apertures 7, provided therefor in the bodies so as to assist in maintaining the clips or 55 brackets in immovable position. The opposite or inner ends of the bodies are slotted at 8, and the material between the slits is struck-out to form fingers or hooks 9, the last mentioned end of the body being round- 60 ed at 10.

A tubular rod or pole 11 has a spring 12 of the coil type extending on its interior and beyond the ends thereof, so that the ends of the spring may be hooked over the fingers 9 of the clips or brackets, whereby it will be seen that the rod or pole is resiliently supported in position, and has its vertical movements limited by the upper end lower edges of the rounded ends 10, in cases where the 70 tube ends extend over and receive said rounded ends of the clips or brackets.

By provision of a coiled spring which is extensible and contractible, it will be evident that the curtain is resiliently supported, and in addition, the spring ends may be drawn apart to accommodate the rod or pole to windows possessed of varying widths, as is evident. As above stated, however, by having a tube or rod or pole of only sufficient 80 length to enable the rounded ends of the body to project thereinto, the rod will be supported against up and down movement, should it be desirable to so hold same.

Having thus described my invention, I claim as new and desire to secure by Letters Patent;—

1. In a curtain support, a pair of clips each having a part which is adapted to project beyond the inner vertical side of a window frame, a finger arranged to the rear of each of said parts, a coil spring connected at its ends to the fingers, and a tubular rod placed over the spring and adapted to be placed in the space between the inner vertical sides of the window frame, the ends of which rod receive said parts whereby the latter restrict the up and down movements of the tubular rod. 90

2. In a curtain support, a pair of clips 100

each having a part which projects inwardly, a coil spring connected at its ends to the clips, and a tubular rod which incloses the spring and receives said parts in its ends, 5 said parts restricting up and down movement of the rod.

In testimony whereof I have signed my

name to this specification in the presence of two subscribing witnesses.

CHARLES L. SHINE.
